Primary Examiner — Ian Simmons*Assistant Examiner* — Rashida C McCoy*(74) Attorney, Agent, or Firm* — Sheridan Ross P.C.(57) **CLAIM**

The ornamental design for convertible shorts, as shown and described.

DESCRIPTION

FIG. 1 is a perspective view of the convertible shorts showing the new design;

FIG. 2 is a front elevation view thereof;

FIG. 3 is a back elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a perspective view showing the convertible shorts of FIG. 1 in a second position of use showing a side zipper in a closed position;

FIG. 9 is a front elevation view thereof;

FIG. 10 is a back elevation view thereof;

FIG. 11 is a left side view thereof, the right side view being a mirror image thereof;

FIG. 12 is a top plan view thereof; and,

FIG. 13 is a bottom plan view thereof.

The dashed lines refer to seams in FIGS. 1-13 and form no part of the claimed design.
